APPARATUS FOR HANDLING AND OPERATING ON MATERIAL

Joseph Sinkovitz, Pittsburgh, Pa., assignor to
Miller Printing Machinery Co., Pittsburgh, Pa.,
a corporation of Pennsylvania

Application August 12, 1941, Serial No. 406,503

27 Claims. (Cl. 101—278)

This invention relates to apparatus for handling and operating on material. It relates to material treating apparatus in combination with material handling apparatus for handling material relatively to the treating apparatus. More particularly, the invention relates to means for relatively moving and guiding means for operating on material and cooperating means for handling material relatively thereto.

While the invention is of general utility I have found it especially applicable to printing or like apparatus. Purely for purposes of explanation and illustration the invention will be described as embodied in printing apparatus. It has especial utility and solves long existing problems in printing or like apparatus, as will presently appear.

Printing apparatus commonly employs a printing couple or press together with a feeder for feeding sheets to the press and a delivery for delivering the printed sheets from the press. It is customary to make the feeder and delivery movable to inoperative positions relatively to the press when the apparatus is not in use to facilitate work on parts which are relatively inaccessible when the portions of the apparatus are assembled in operative position. What will be said below applies to both the feeder and the delivery but for illustrative purposes the delivery will be considered as an example and the specific description will be directed particularly to application of the invention to a delivery.

It is desirable to be able to remove and replace the delivery pile support either from the side of the delivery or from the end thereof. With deliveries pivotally connected with the press by a vertical pivot at the corner of the press it has been possible to provide for removing the pile support from the side of the delivery or from the end of the delivery. However, this has not been the case with deliveries of the so-called "roll-away" type which are bodily separable from and movable toward and away from the press. Deliveries of this type are ordinarily supported and guided for movement relatively to the press upon rails or tracks extending out from the press and mounted upon the press room floor. It is of course important that the delivery move into proper cooperative relationship with respect to the press when the press is to be operated so that the parts of the press and delivery will function cooperatively in the intended manner. By the use of rails or similar elongated guiding and supporting means projecting upwardly from the press room floor this result has been accomplished.

However, the provision of such rails or similar means at both sides of the delivery has interfered with removal of the pile support from the side of the delivery and in such deliveries the pile support has been removed from the end. The pile support with the pile of sheets thereon is heavy, its weight sometimes running well into the thousands of pounds, and the loaded pile support is preferably removed from the delivery by a lift truck or similar device which is rolled under the pile support when at the bottom of its vertical path of movement in the delivery. Any means projecting upwardly from the press room floor at the sides of the delivery interferes with thus removing the pile support. On the other hand, the proper registry of the delivery to the press is important and this has been accomplished by the use of elongated guiding and supporting means extending out from the press as above explained. The result has been that in deliveries of the type in question it has been necessary to remove the loaded pile support from the end of the delivery, which has in many cases entailed great inconvenience since it is frequently preferable due to press room arrangement and for other reasons to remove the loaded pile support from the side of the delivery.

I have devised apparatus obviating all of the disadvantages above mentioned. I provide for removing and replacing the pile support from the side of a rollaway delivery while at the same time insuring proper guiding and supporting of the delivery in its movements relatively to the press and proper registry of the delivery to the press when in operative position relatively thereto. I preferably provide guiding and supporting means interposed between the delivery and the press room floor enabling free lateral access to the pile support from one side of the delivery. I prefer to employ one guide rail or track extending out from the press and underlying the delivery adjacent one side thereof. I preferably support the opposite side of the delivery by means engaging the press room floor and offset longitudinally from the pile support. This means that the delivery may be supported and guided upon a rail at one side and upon the floor at the other side. However, due to irregularities in the floor the second mentioned side of the delivery is not guided with the accuracy required to insure proper registry of the delivery to the press when the delivery is moved into operative position relatively to the press. Consequently I provide additional means for insuring proper registry of the delivery to the press, such means preferably being disposed at

the side of the delivery which is supported directly upon the floor and becoming operative to insure proper elevation of that side of the delivery as the delivery moves into operative position relatively to the press. I provide for vertical adjustment at the side of the delivery supported upon the floor so that the delivery may be level.

Other details, objects and advantages of the invention will become apparent as the following description of a present preferred embodiment thereof proceeds.

In the accompanying drawings I have shown a present preferred embodiment of the invention, in which

Figure 1 is a fragmentary side elevational view of a sheet delivery shown in operative position relatively to a press;

Figure 2 is a view similar to Figure 1 showing the delivery moved out away from the press to inoperative position;

Figure 3 is an end elevational view of the delivery as seen from the left in Figures 1 and 2;

Figure 4 is a detail fragmentary side elevational view to enlarged scale of a portion of the apparatus as shown in Figure 1; and

Figure 5 is a detail fragmentary horizontal cross-sectional view of the structure shown in Figure 4 and taken on the line V—V of Figure 3.

Referring now more particularly to the drawings, there is shown a printing press designated generally by reference numeral 2 and which is of the flat bed and cylinder type, the printing cylinder being indicated at 3. The press comprises the usual opposed side frames 4 which carry the operating mechanism thereof. Adapted for co-operation with the press 2 is a delivery designated generally by reference numeral 5, the delivery being of the so-called "rollaway" type which is bodily movable toward and from the press. The delivery is shown in operative position relatively to the press in Figure 1 and in inoperative position relatively to the press in Figure 2.

The delivery comprises a pile support 6 carried in the usual way by cables 7. The pile support 6 is provided with legs 8 so that when the pile support is filled and is lowered to the bottom of its path of vertical travel in the delivery the bottoms of the legs 8 will rest upon and support the pile support and its load from the floor 9 as indicated in chain lines in Figures 1 and 2. The delivery is open at its end as shown in Figure 3 to enable removal of the pile support and it is also open opposite the pile support at the side of the delivery nearest the eye viewing Figures 1 and 2. Thus the pile support may be removed and replaced either from the end or from the side.

In order to provide for removal of the pile support from the side of the delivery while at the same time insuring proper supporting and guiding of the delivery and proper registry thereof relatively to the press when the delivery is moved into cooperative position relatively to the press I provide supporting and guiding means for the delivery now to be described. Mounted upon the floor 9 and extending outwardly from the press below one side of the delivery is a track or rail 10. The delivery has opposed side frames 11 and 12, the former of which has a downward projection 13 interlocking with the rail 10 as shown in Figure 3 to insure proper positioning and guiding of the delivery relatively to the rail and to prevent tilting of the delivery. Rollers 75

14 are interposed between the rail 10 and a downwardly facing horizontal surface 15 of the side frame 11. The side of the delivery above the rail 10 is supported and guided upon such rail 5 and is moved in and out relatively to the press upon the rollers 14.

The side of the delivery at which the side frame 12 is positioned is supported primarily directly from the press room floor, there being no rail or other guiding means extending upwardly from the press room floor at that side of the delivery. The delivery frame has a downward extension 16 to which is connected by screws 17 a beam 18. The beam 18 is rigidly fastened to 15 the delivery so as to form in effect an integral part thereof and extends directly toward the press in a direction parallel to the length of the rail 10. The beam 18 has at its end at which it is connected with the delivery frame portion 16 a horizontal cylindrical bore 19. Entering such bore and fitting snugly therein is the cylindrical end 20 of an axle 21. The axle 21 has an enlarged cylindrical end portion 22 at its end opposite the end 20 and coaxial therewith. The 20 delivery side frame 12 has a downward extension 26 in which the enlarged cylindrical end portion 22 of the axle 21 is snugly received. Intermediate the coaxial cylindrical end portions 20 and 22 the axle 21 has an eccentric supporting portion 23. Mounted upon the supporting portion 23 and keyed thereto by a key 23a is a hub-like bushing 24 upon which is journaled for rotation a rubber faced band-like wheel or roller 25. The rubber faced wheel 25 bears directly upon the floor 9.

The elevation of the wheel relatively to the feeder may be adjusted simply by turning the axle 21 within its mountings in the frame portions 16 and 26. To facilitate such turning the outer end portion 22 of the axle is provided with a groove 27. The frame portion 26 has a generally longitudinally extending substantially horizontal bore 28 into which extends a pin 29 having a curved cut-out portion at 30 partially embracing the cylindrical end portion 22 of the axle 21, as shown in Figure 4. The outer end of the pin 29 is threaded as shown at 31 and provided with a nut 32 adapted to bear against the end surface of the frame portion 26. When the nut 32 is turned out so that the pin is loose in the bore 28 the axle 21 is free to be turned. After the axle has been turned to the desired angular position to bring the wheel 25 to the desired elevation relatively to the feeder the nut 32 is tightened up against the end surface of the frame portion 26 which draws the pin 29 toward the left, viewing Figure 4, to frictionally engage the portion 22 of the axle 21 and thereby hold the axle against turning. In Figure 4 the axle 21 is shown in the position in which the wheel 25 is at its highest possible point relatively to the feeder; in other words, the wheel supporting portion 23 of the axle 21 is in its upward dead center position. Turning of the axle in either direction from this position lowers the wheel 25.

The wheel 25 is longitudinally offset from the pile support 6, as shown in Figures 1 and 2, so as to allow free access to the pile support from the side of the delivery at which the wheel 25 is disposed. At such side of the delivery the delivery frame is so formed as to provide an opening in transverse alignment with the pile support and extending from the bottom of the frame to a point high enough so that the loaded pile support after being lowered to the floor as shown in chain lines in Figures 1 and 2 can be picked up and removed

laterally from the delivery by a lift truck or similar device. There is nothing to interfere with wheeling the lift truck in under the pile support when in the chain line position of Figures 1 and 2.

The beam 18 has at its top a horizontal flange 33 extending generally outwardly as shown in Figure 5. Thus the beam 18 has a vertical web portion and a horizontal outwardly extending flange at its top. Mounted in the side frame 4 of the press 2 at the same side of the apparatus as the wheel 25 are two rollers 34 and 35 positioned to receive the flange 33 of the beam 18 between them so that when the delivery is moved into cooperative position relatively to the press the side of the delivery at which the wheel 25 is positioned will be brought to the proper elevation to insure proper registry of the delivery to the press. The opposite side of the delivery is precisely positioned in the vertical direction by the rail 10, but the rubber faced wheel 25 only approximately positions in the vertical direction the side of the delivery at which the wheel is positioned, precise positioning being practically impossible due to irregularities in the floor and wear of and irregularity and variations of loading upon the rubber face of the wheel 25. However, when the delivery moves in to operative position relatively to the press a substantial portion of the weight of the delivery is carried by the press frame through the rollers 34 and 35, thus transferring much of the load of the delivery from the wheel 25.

The positioning of the rollers 34 and 35 is such that the side of the delivery at which the beam 18 is connected thereto is brought precisely to the desired elevation to insure proper registry of the delivery with the press. The lower roller 35 underlies the flange 33 of the beam 18 and the upper roller 34 overlies the beam as shown in Figure 5. Thus despite the elimination of any supporting and guiding rail at one side of the delivery to provide for removal and replacement of the pile support from that side the delivery may be properly and accurately registered to the press when it is moved into cooperative relationship with respect thereto.

While I have shown and described a present preferred embodiment of the invention it is to be distinctly understood that the invention is not limited thereto but may be otherwise variously embodied within the scope of the following claims.

I claim:

1. Apparatus for handling and operating on material comprising an operating unit, a handling unit cooperable with the operating unit, the handling unit being movable bodily upon a floor relatively to the operating unit toward and from operative position with respect thereto, a guide rail on the floor at one side only of the handling unit for guiding the handling unit in its movements relatively to the operating unit, the handling unit carrying a wheel at its opposite side directly engaging the floor, a guide beam projecting from the handling unit adjacent the second mentioned side thereof and means on the operating unit cooperating with said guide beam for additionally guiding the handling unit.

2. Apparatus for handling and operating on material comprising an operating unit, a handling unit cooperable with the operating unit and movable bodily relatively to the operating unit toward and from operative position with respect thereto, guide means stationary relatively to the operating unit disposed adjacent one side of the handling unit for guiding the handling unit in its

movements relatively to the operating unit and additional guide means for the handling unit connected therewith adjacent the opposite side thereof and movable therewith to further guide the handling unit relatively to the operating unit.

3. Apparatus for handling and operating on material comprising an operating unit, a handling unit cooperable with the operating unit and movable bodily relatively to the operating unit 10 toward and from operative position with respect thereto, a guide rail upon which the handling unit rides in its movements relatively to the operating unit, said guide rail being disposed adjacent one side of the handling unit, a guide beam 15 projecting from the handling unit adjacent its opposite side and means on the operating unit cooperating with said guide beam for additionally guiding the handling unit.

4. Apparatus for handling and operating on 20 material comprising an operating unit, a handling unit cooperable with the operating unit, a support, the handling unit being movable bodily relatively to the operating unit toward and from operative position with respect thereto 25 while supported by the support, guide means carried by the support at one side of the handling unit to guide the handling unit in its movements relatively to the operating unit, the handling unit having anti-friction means at its opposite 30 side directly engaging the support, and additional guide means for the handling unit connected therewith adjacent the second mentioned side thereof and movable therewith to further guide the handling unit relatively to the operating 35 unit.

5. Apparatus for handling and operating on material comprising an operating unit, a handling unit cooperable with the operating unit and movable bodily relatively to the operating unit 40 toward and from operative position with respect thereto, guide means for guiding the handling unit in its movements relatively to the operating unit disposed adjacent one side of the handling unit and effective to predeterminedly position that side of the handling unit as to height and means connected with the handling unit at the opposite side thereof and extending between the handling unit and the operating unit for insuring corresponding positioning of such second mentioned side of the handling unit as to height upon movement of the handling unit toward the operating unit.

6. Apparatus for handling and operating on material comprising an operating unit, a handling unit cooperable with the operating unit and movable bodily relatively to the operating unit toward and from operative position with respect thereto, means for supporting one side of the handling unit at precisely predetermined height 55 during its movements relatively to the operating unit, means for supporting the opposite side of the handling unit at approximately predetermined height during such movements and means for insuring positioning of the second mentioned side of the handling unit at precisely predetermined height upon movement of the handling unit into operative position with respect to the operating unit.

7. Apparatus for handling and operating on 60 material comprising an operating unit, a handling unit cooperable with the operating unit and movable bodily relatively to the operating unit toward and from operative position with respect thereto, means for supporting one side of the handling unit at precisely predetermined height 65

during its movements relatively to the operating unit, means for supporting the opposite side of the handling unit at approximately predetermined height during such movements, a beam rigidly connected with the handling unit at the second mentioned side thereof and extending parallel to the direction of movement of the handling unit relatively to the operating unit and means on the operating unit cooperating with said beam to insure positioning of the second mentioned side of the handling unit at precisely predetermined height upon movement of the handling unit into operative position with respect to the operating unit.

8. Printing or like apparatus comprising a press and sheet handling means bodily separable from and movable toward and away from the press, said sheet handling means including a pile support which is removable from the sheet handling means in a direction transversely of the general direction of movement of the sheet handling means toward and away from the press.

9. Printing or like apparatus comprising a press and sheet handling means bodily separable from and movable toward and away from the press, the sheet handling means including a pile support and having a pile support removing and replacing opening extending to the floor at one side of the sheet handling means.

10. Printing or like apparatus comprising a press and sheet handling means bodily separable from and movable toward and away from the press, the sheet handling means including a pile support and having pile support removing and replacing openings extending to the floor at one side and one end of the sheet handling means.

11. Printing or like apparatus comprising a press and sheet handling means bodily separable from and movable toward and away from the press, the sheet handling means including a pile support and having a pile support removing and replacing opening extending upwardly from its bottom at one side of the sheet handling means, the sheet handling means being supported at said side by means longitudinally offset from said opening.

12. Sheet handling apparatus comprising a sheet handling unit adapted to move bodily toward and away from a press or the like, means including an elongated supporting and guiding member underlying the unit at one side thereof, wheel means lying directly on the floor for supporting the unit at the opposite side thereof and means for altering at will the relative vertical positions of the unit and wheel means.

13. Printing or like apparatus comprising a press and sheet handling means bodily separable from and movable toward and away from the press, means including an elongated supporting and guiding member underlying the sheet handling means at one side thereof and means including a member fastened to the sheet handling means and extending to the press for supporting the sheet handling means at the opposite side thereof.

14. Printing or like apparatus comprising a press and sheet handling means bodily separable from and movable toward and away from the press, means including an elongated supporting and guiding member underlying the sheet handling means at one side thereof and means including wheel means lying directly on the floor and a member fastened to the sheet handling means and extending to the press for supporting

the sheet handling means at the opposite side thereof.

15. Printing or like apparatus comprising a press and sheet handling means bodily separable from and movable toward and away from the press, means for supporting one side of the sheet handling means at precisely predetermined height during its movements relatively to the press, means for supporting the opposite side 10 of the sheet handling means at approximately predetermined height during such movements and means for insuring positioning of the second mentioned side of the sheet handling means at precisely predetermined height upon movement of the sheet handling means into operative position with respect to the press.

16. Printing or like apparatus comprising a press and sheet handling means bodily separable from and movable toward and away from the press, the sheet handling means including a pile support and having a pile support removing and replacing opening at one side thereof, means for supporting the opposite side of the sheet handling means at precisely predetermined height during its movements relatively to the press and means for supporting the first mentioned side of the sheet handling means at approximately predetermined height during such movements and at precisely predetermined height when the sheet handling means is in operative position with respect to the press.

17. Printing or like apparatus comprising a press and sheet handling means bodily separable from and movable toward and away from the press, the sheet handling means including a pile support and having a pile support removing and replacing opening at one side thereof, means including a track underlying the sheet handling means for supporting the opposite side 40 thereof at precisely predetermined height during its movements relatively to the press and means including wheel means longitudinally offset from said opening and lying directly upon the floor for supporting the first mentioned side of the sheet handling means at approximately predetermined height during such movements.

18. Sheet handling apparatus comprising a sheet handling unit adapted to move bodily toward and away from a press or the like, said 50 unit including a generally vertically movable pile support, and means adapted to be interposed between the floor and said pile support when the pile support is in its lowermost position to position the pile support above the floor, the sheet handling unit having a lateral opening 55 extending upwardly from its bottom in transverse alignment with the pile support so that the pile support may easily be removed and replaced by a lift truck or the like from its aforementioned position in the sheet handling unit.

19. Sheet handling apparatus comprising a sheet handling unit adapted to move bodily toward and away from a press or the like, said unit including a pile support and a lateral opening 65 in transverse alignment with said pile support through which the pile support may be inserted and removed, means including a supporting and guiding rail underlying said unit adjacent the side opposite the side containing said opening and vertically adjustable means cooperating directly with the floor and offset longitudinally from said opening for supporting the side of said unit containing said opening.

20. Printing or like apparatus comprising a press and sheet handling means bodily separat-

75

able from and movable toward and away from the press, the sheet handling means having a beam connected rigidly therewith and extending toward the press in a direction substantially parallel to the direction of movement of the sheet handling means relatively to the press, and rollers on the press receiving said beam whereby the portion of the sheet handling means adjacent said beam is brought to properly adjusted height when the sheet handling means moves to its operative position adjacent the press.

21. Printing or like apparatus comprising a press and sheet handling means bodily separable from and movable toward and away from the press, means for supporting one side of the sheet handling means at precisely predetermined height during its movements relatively to the press, means including a wheel on the sheet handling means engaging the floor for supporting the opposite side of the sheet handling means at approximately predetermined height during such movements, a beam connected rigidly with the sheet handling means adjacent the second mentioned side thereof and extending toward the press in a direction substantially parallel to the direction of movement of the sheet handling means relatively to the press and means on the press receiving said beam whereby the second mentioned side of the sheet handling means is brought to precisely predetermined height when the sheet handling means moves to its operative position adjacent the press.

22. Apparatus for handling and operating on material comprising an operating unit, a handling unit cooperable with the operating unit and movable bodily relatively thereto toward and from operative position with respect thereto and having a permanently open side, and guiding means for guiding the handling unit in such movements, said guiding means being arranged so as to partially obstruct free access to the handling unit from the side opposite said first mentioned side in a direction transversely of said guiding means but to provide free access to the handling unit from said first mentioned side so that material may be freely transferred to or from the handling unit at said first mentioned side.

23. Apparatus for handling and operating on material comprising an operating unit, a handling unit cooperable with the operating unit and having a permanently open side, a support, the handling unit being movable bodily relatively to the operating unit toward and from operative position with respect thereto while supported by the support, and guide means for the handling unit on the support, said guide means projecting from the support at the side opposite said first mentioned side only of the handling

unit so as to provide for free access to the handling unit adjacent the support at said first mentioned side of the handling unit.

24. Apparatus for handling and operating on material comprising an operating unit, a handling unit cooperable with the operating unit and having a removable material carrier, the handling unit being movable bodily relatively to the operating unit toward and from operative position with respect thereto and having a permanently open side, and guide means for the handling unit arranged so as to obstruct free removal of the material carrier from the handling unit at the side opposite said first mentioned side thereof while leaving said first mentioned side of the handling unit unobstructed whereby the material carrier may be freely removed from and replaced in the handling unit at said first mentioned side thereof.

25. Apparatus for handling and operating on material comprising an operating unit, a handling unit cooperable with the operating unit and movable bodily relatively to the operating unit toward and from operative position with respect thereto and having a permanently open side, and guide rail means disposed adjacent the side opposite said first mentioned side only of the handling unit for guiding the handling unit in its movements relatively to the operating unit, said first mentioned side of the handling unit being unobstructed so that material may be freely transferred to or from the handling unit at said first mentioned side thereof.

26. Apparatus for handling and operating on material comprising an operating unit, a handling unit cooperable with the operating unit and having a permanently open side, a support, the handling unit being movable bodily relatively to the operating unit toward and from operative position with respect thereto while supported by the support, and a guide rail interposed between the handling unit and the support at the side opposite said first mentioned side only of the handling unit, the handling unit having anti-friction means at said first mentioned side directly engaging the support.

27. Apparatus for handling and operating on material comprising an operating unit, a handling unit cooperable with the operating unit and having a permanently open side, the handling unit being movable bodily upon a floor relatively to the operating unit toward and from operative position with respect thereto, and a guide rail on the floor at the side opposite said first mentioned side only of the handling unit for guiding the handling unit in its movements relatively to the operating unit, the handling unit carrying a wheel engaging the floor at said first mentioned side of the handling unit.

JOSEPH SINKOVITZ.
